ADJUSTABLE CHAIN PIPE WRENCH

Carl M. Henry, 1956 Franklin Ave.,
Toledo, Ohio 43624

Filed Dec. 16, 1974, Ser. No. 533,288

Term of patent 14 years

Int. Cl. D8—05

U.S. Cl. D8—22

FIG. 1

FIG. 2

FIG. 3

FIG. 1 is a front elevational view of an adjustable chain pipe wrench, showing my new design;

FIG. 2 is a side elevational view thereof, with broken line disclosure for illustrative purposes only;

FIG. 3 is a rear elevational view thereof.

I claim:

The ornamental design for an adjustable chain pipe wrench, as shown and described.
